UNITED STATES PATENT OFFICE

2,475,632

BULLET

Wiley T. Moore, United States Army, Laverne, Okla., and Wilfred E. Thibodeau, Cleveland, Ohio, assignors to the United States of America as represented by the Secretary of War

Application March 19, 1942, Serial No. 435,318

8 Claims. (Cl. 102—90)

(Granted under the act of March 3, 1883, as amended April 30, 1928; 370 O. G. 757)

1

The invention described herein may be manufactured and used by or for the Government for governmental purposes without the payment to us of any royalty thereon.

This invention relates to a bullet, and in particular to a bullet for use with small and medium arms. While the bullet may be loaded partly or wholly with high explosive, it is intended principally as a carrier for incendiary material.

In a properly designed bullet the modern types of incendiary compositions will ignite on impact without any special percussion mechanism. The conditions of intended use of the bullet will in large measure affect the design thereof. For example, a successful attack on the gasoline tank of an airplane requires that the incendiary powers of a bullet be effective after it has passed through an outer armor and traversed some distance therebeyond. This may be accomplished by delaying ignition beyond initial impact or by maintaining the incendiary outburst for a time after initiation. The bullet of the invention is well adapted to accomplish the latter although it is not intended to be limited to such functioning.

It is known to use a hollow bullet with thin nose and filled with incendiary material. Such bullets, however, are not designed for penetration, but are entirely collapsible on impact and therefore limited in use with respect to present day requirements. The bullet of the invention provides a reinforcement in the form of an inner sleeve which is efficacious in many respects even though the precise phenomena basically responsible for its successful employment are not entirely understood. It would appear, however, that the reinforcing sleeve serves to retain the form of the main body of the bullet while penetration of the target is effected after initiation; and it would further appear that there is some sort of coaction between the forward edge of the sleeve and the ogive which conspires to produce a more effective initiation of the incendiary composition than is usual with a simple, loaded, hollow shell, the sleeve being more or less free to advance in advance of the bullet body as the ogive is checked in flight and collapsed.

It is therefore an object of the invention to produce a charged bullet which will preserve its body form during penetration.

It is a further object of the invention to produce a reinforced incendiary bullet.

It is a further object of the invention to produce a hollow bullet having an inner sleeve reinforcement movable relative to the body of the bullet.

2

It is a further object of the invention to produce an incendiary bullet effective to ignite a target after penetration of an outer armor thereon.

To these and other ends, the invention consists in the construction, arrangement and combination of elements described hereinafter and pointed out in the claims forming a part of this specification.

10 A practical embodiment of the invention is illustrated in the accompanying drawing wherein:

Figure 1 is a view in axial section of a bullet embodying one form of the invention, and

15 Figures 2, 3 and 4 are fragmentary sectional views showing modifications.

Referring to the drawing by characters of reference there is shown a jacket 1 which in the preferred form is of gilding metal but which may be of any suitable material, a lead lining 2 and an inner sleeve 3 of tough material, preferably steel. This sleeve may be keyed to the projectile body proper, but preferably it will be movable with respect thereto under forces of the order of those engendered on impact.

20 25 The lead lining is shown as terminating coincident with the ends of the steel sleeve but of course this lining may be longer or shorter and of different thicknesses. In particular the lining may be omitted and the projectile body may be composed of the steel sleeve alone as shown at 4 in Figure 3.

While the steel sleeve is shown as having an annular protuberance 5 (Figure 1) to promote firing on impact, the size or shape may be varied, and, in particular, may be omitted as shown in Figure 2. The steel sleeve should extend to, and preferably somewhat into the ogive and is adapted to bullets of varying profile with long or short ogives, the bullet shown with long ogive being for illustrative purposes only. A main function of the steel sleeve is to preserve the body portion from disruption, but it has been found that better detonation results are obtained if the sleeve extends into the ogive.

40 45 Included in the ogive and within steel sleeve 3 is the incendiary composition 6 which may be loaded in any convenient manner, for instance, by pouring in increments and pressing, or by inserting preformed pellets. The charge may be incendiary composition or high explosive or a combination of increments of both arranged to suit any particular purpose.

A steel disk 7 is provided over the rear of the sleeve and lining to protect the charge against 50 55 the effects of propellant gases and the rear end

is secured in any convenient manner as by the screwed cap 8 of Figure 1 or by turning over the jacket 1 as shown in Figure 4.

We claim:

1. A projectile comprising an outer jacket having a body portion and an ogival portion, a tubular sleeve in said projectile occupying said body portion but terminating short of the point of said ogival portion, and a charge in said ogive and within said tubular sleeve said sleeve being separate from said jacket and slideable forwardly relatively thereto on impact and crushing of said ogive.

2. A projectile comprising an outer jacket having a body portion and an ogival portion, a tubular sleeve in said projectile occupying said body portion but terminating short of the point of said ogival portion, a lead lining between said sleeve and said jacket, and a charge in said ogive and within said tubular sleeve.

3. A projectile comprising an outer jacket having a body portion and an ogival portion, a tubular steel sleeve within and nesting with said jacket, said sleeve occupying said body portion but terminating short of the point of said ogival portion, and a charge in said ogive and within said tubular sleeve said sleeve being separate from said jacket and slideable forwardly relatively thereto on impact and crushing of said ogive.

4. A projectile comprising an outer jacket having a body portion and an ogival portion, a tubular sleeve in said projectile occupying said body portion but terminating short of the point of said ogival portion, a lead lining between said sleeve and said jacket, the interface between said sleeve and said lining being defined by a cylindrical surface whereby said tube is conditioned to move forward relative to said lining on impact.

5. A projectile comprising an outer jacket having a body portion and an ogival portion, a tubular steel sleeve in said projectile slideably fitting said jacket, said sleeve occupying said body portion and extending into the ogival portion but terminating short of the point thereof and an incendiary charge in said ogival portion.

6. In a projectile, a jacket having a smooth exterior formed by a cylindrical portion tapering at one end to a point to thereby form an ogival portion, said portions joining in a plane normal to the axis of said cylindrical portion, a tubular steel sleeve in said jacket and substantially co-extensive with and coaxial of said cylindrical portion, said sleeve terminating between said plane and point and being separate from said jacket and slideable forwardly relatively thereto on impact and crushing of said ogival portion.

7. In a projectile, a jacket having a smooth exterior formed by a substantially cylindrical portion tapering at one end to form an ogival portion, a tubular steel sleeve in said jacket and positioned with its axis coincident with the axis of said jacket, said sleeve being of less outer diameter than the inside diameter of said cylindrical portion and having its rear end substantially coincident with the rear of said jacket, and its forward end terminating within said ogival portion but short of the nose of said jacket, the forward end of said sleeve having an integral inward protuberance forming a throat of reduced cross sectional area, the outer forward rim of said sleeve being in substantial contact with the inner surface of said jacket, an explosive charge filling said sleeve and the ogival portion of said jacket forwardly of said rim, means closing the rear end of said jacket, and means between said jacket and sleeve adapted to guide said sleeve in forward movement relatively to said jacket on impact and crushing of the nose of said jacket.

8. In a projectile, a jacket having a smooth exterior formed by a cylindrical portion tapering at one end to a point to thereby form an ogival portion, said portions joining in a plane normal to the axis of said cylindrical portion, a tubular steel sleeve in said jacket and substantially co-extensive with and coaxial of said cylindrical portion, said sleeve terminating between said plane and point and being separate from said jacket and slideable forwardly relatively thereto on impact and crushing of said ogival portion, said sleeve having an outer diameter less than the inner diameter of said jacket whereby to form a space between said sleeve and jacket, annular in cross section, and a lead lining filling said annular space.
